(57) CLAIM

The ornamental design for a footwear as shown and described.

DESCRIPTION

FIG. 1 is a top, front, and right side perspective view of a footwear in accordance with this invention.

FIG. 2 is a right side view thereof.

FIG. 3 is a left side view thereof.

FIG. 4 is a front view thereof.

FIG. 5 is a rear view thereof.

FIG. 6 is a top view thereof.

FIG. 7 is a bottom view thereof.

FIG. 8 is a bottom, rear, and left side perspective view thereof; and,

FIG. 9 is a cross-sectional view thereof taken along section line 9-9 in FIG. 7.

The broken lines in the drawings show environmental structure of the footwear that forms no part of the claimed design.
